UNITED STATES PATENT OFFICE.

GEORGE C. GARDNER, OF CHICAGO, ILLINOIS.

DESIGN FOR A DOOR-HANGER FRAME.

SPECIFICATION forming part of Design No. 27,142, dated June 1, 1897.

Application filed April 19, 1897. Serial No. 632,867. Term of patent 7 years.

To all whom it may concern:

Be it known that I, GEORGE C. GARDNER, a citizen of the United States of America, residing at Chicago, in the county of Cook and State of Illinois, have invented a certain new and original Design for a Door-Hanger Frame, of which the following is a specification.

My invention relates to a certain new and original design for a frame for door-hangers, the same being illustrated by means of the accompanying drawings, in which—

Figure 1 is a side elevation of the design; Fig. 2, a transverse section in line 2 2 of Fig. 1, and Fig. 3 a similar section in line 3 3 of Fig. 1.

Referring to the drawings, the frame, which is the subject of this application, will be seen to consist of an upper portion A, extending downward into a lower portion B. Both portions are of even thickness and comparatively thin and have forwardly-extending ribs or corrugations $a b b'$, uniting at $a' a'$, the corrugation a being circular in gen-

eral outline and the corrugations $b b'$ being substantially parallel and united at the bottom by a similar corrugation b^3 . In these corrugations are circular openings $b^4 b^5 b^6 b^7$, surrounded by outwardly-extending circular corrugations b^8 of greater diameter than the corrugations $b b'$ and merging into the same at their intersections therewith.

The essential features of my design I consider to be the frame, of substantially uniform thickness, having the outwardly-extending corrugations $b b'$, containing the openings $b^4 b^5 b^6 b^7$, surrounded by outwardly-extending circular corrugations wider than the corrugations $b b'$ and merging into the same at their intersections therewith.

I claim as new and desire to secure by Letters Patent—

The design for a frame for door-hangers herein shown and described.

GEORGE C. GARDNER.
